UNITED STATES PATENT OFFICE

2,484,741

ROTARY MARSH LAND DITCHER

Washington Etienne Rodriguez, Larose, La.

Application October 22, 1947, Serial No. 781,263

4 Claims. (Cl. 37—70)

1

My present invention relates generally to excavating, dredging, or digging, and more specifically to an improved rotary ditcher for marshlands, of the floating and self-propelled type, which while well adapted for various purposes and uses, is especially designed for use in cutting channels or dredging and digging lateral drain ditches.

The primary object of the invention is the provision of an appliance of this type by means of which the soil or mud from marshlands or swamplands may readily be removed and deposited laterally of the resulting ditch, and thereby form a channel of water for the float or pontoon forming the supporting base for the operating mechanism. The appliance is equipped with a pair of oppositely revolving, and combined rotary diggers and propellers for forming the ditch and propelling the craft, and motor operated means are employed with power transmission mechanism under manual control for operating the combined diggers and propellers.

The invention consists essentially in certain novel features of construction and combinations and arrangements of parts as will hereinafter be described and more particularly set forth in the appended claims; and the invention includes a minimum number of parts that may with facility be manufactured at low cost of production, and the parts may be assembled with convenience to constitute a durable and efficient craft or appliance that performs its functions with a minimum expenditure of time and labor.

In the accompanying drawings I have illustrated one complete example, and a modification, of an appliance in which my invention is physically embodied according to one mode I have so far devised for the practical application of the principles of the invention. It will however be understood that changes and alterations are contemplated and may be made in these exemplifying drawings and mechanical structures, within the scope of my claims, without departing from the principles of my invention.

Figure 1 is a plan view of the water-craft or hull, with the removable deck omitted, equipped with the ditching mechanism of my invention.

Figure 2 is a longitudinal vertical sectional view, including the removable deck or cover, as at line 2—2 of Fig. 1.

Figure 3 is a top plan view of the craft with the deck thereon.

Figure 4 is an enlarged detail front elevation showing the pair of oppositely revolving com-

2

bined rotary diggers and propellers, together with the rear mud-guard.

Figure 5 is a view similar to Fig. 4 showing a modified arrangement of the rotary blades, together with a cross-section of the ditch.

Figure 6 is a detail section at line 6—6 of Fig. 4 through one of the straight bevel-edge blades of the rotary diggers.

Figure 7 is a transverse vertical sectional view at line 7—7 of Fig. 1 showing the sprocket chain drive for the two oppositely revolving operating shafts.

Figure 8 is an enlarged longitudinal vertical sectional view at line 8—8 of Fig. 1 showing the concentrically arranged operating shafts and the hub portions of the rotary diggers.

Figure 9 is a transverse horizontal sectional view at line 9—9 of Fig. 2 showing the power reducing, reversing and transmission gears.

20 In the physical embodiment of my invention I employ a scow, pontoon or hull P of desired size and shape that may be equipped with necessary accessories and that is substantially hollow having a bottom and upwardly extended sides and ends, and which is provided with a bow E, a stern F, and a deck D having required hatches, as H, H. The hull is equipped with a suitable motor M and its control lever L for manual use by an operator stationed on the deck covering, the motor, the 25 power transmission mechanism and the operating mechanism being mounted upon a main frame of channel bars or girders 1 and 2. The longitudinal girders and spaced cross beams 3, 3 of the frame are rigidly supported within the interior of the hull, and the motor shaft 4 is journaled in bearings B of a transversely arranged gear box 5 located at the approximate longitudinal center of the craft.

Within the gear box are mounted power transmission gearing for reducing the speed of the motor shaft, which gearing, as best seen in Fig. 40 9 includes a pinion 6 on the shaft 4 that meshes with a larger gear 7 mounted on the gear shaft 8 that is journaled in bearings B, B, and a driving gear 9 on shaft 8 meshes with a driven gear 10 on the operating shaft 11 to reverse same, which is axially aligned with the motor shaft, and extends forwardly through the bow end of the hull, with suitable bearings B, B.

45 As best seen in Fig. 7 the gear shaft 8 operates a sprocket chain drive including a sprocket wheel 12, a driven sprocket wheel 13, and a sprocket chain 14, the sprocket wheel 13 being mounted upon the rear end of a tubular operating shaft 50 15 that is concentrically arranged on the operat-

ing shaft 11 and provided with anti-friction bearings 16, and also journaled in usual bearings B, B.

By means of the chain-drive the tubular shaft is rotated in a direction opposite to the operating shaft 11, which is reversed by gears 9 and 10 and the front ends of both of these operating shafts project forwardly through the front end E of the hull, where hubs 17 and 18 are rigidly mounted upon the tubular shaft and the enclosed shaft, respectively, and separated by a thrust washer 19.

The two oppositely revolving rotary cutters digger-propellers 20, 21 are made up of four blades each that are rigidly affixed to the central hubs 18 and 17, and the straight blades of Fig. 4 at their outer ends terminate in inclined flanges providing diggers or scoops 22 that remove the soil or mud from the swamp or marsh and deposit it laterally as indicated by the arrows in Fig. 5 at the opposite sides of the ditch as the appliance advances through the channel being cut.

As indicated in Fig. 6 the blades are formed with beveled edges as at 23 and the flanges at the tips are sloped to insure a propelling movement of the rotary diggers for advancing the floating hull.

Various changes and alterations may be made in the disclosure of the invention, as for instance, in Fig. 5 the combined diggers and propellers may have curved blades as 24 in lieu of the straight blades in Fig. 4, and these blades 24 are equipped with the cutters or diggers 22 and the bevel edges 23 for efficient performance of the digger-propellers.

As thus described it will be apparent that the self-propelled craft is capable of cutting a channel or ditch with a sufficient depth of water to accommodate its hull, and by means of the rotary diggers a cleanly-cut and straight drain ditch is fashioned through the marshland or swamp for desired purposes.

Having thus fully described my invention, what I claim as new and desire to secure by Letters Patent is:

1. In a ditch forming machine, the combination which comprises an elongated substantially hollow hull having a bottom with upwardly extended sides and ends, a plurality of spaced aligned rotary cutters having hubs with radially disposed blades thereon spaced from one end of the hull, the diameter of said rotary cutters being sufficient to cut a ditch the width and depth of which is greater than the width and depth of the hull, the tips of said blades formed to provide propelling means for the hull in the ditch with the hull floating on water therein as the cutters rotate, a centrally disposed shaft longitudinally positioned in and extended from the end of the hull from which the rotary cutters extend and on which one of said rotary cutters is carried, a tubular shaft surrounding a portion of said centrally disposed shaft and on which another one of the cutters is carried and means rotating the cutters through the shaft with one cutter turning clockwise and the other counterclockwise.

2. In a ditch forming machine, the combination which comprises an elongated substantially hollow hull, a plurality of spaced aligned rotary cutters having hubs with radially disposed blades thereon spaced from one end of the hull, a centrally disposed shaft longitudinally positioned in and extended from the end of the hull from which the rotary cutters extend and on which one of the said rotary cutters is carried, a tubular shaft

surrounding a portion of said centrally disposed shaft and on which another one of the cutters is carried the diameter of said rotary cutters being sufficient to cut a ditch the width and depth of which is greater than the width and depth of the hull, the outer edges of the blades of said cutters being beveled and tips of said blades being inclined rearwardly and outwardly providing propelling means for the hull in the ditch with the hull floating on water in the ditch, and means rotating the cutters through the shafts with one cutter turning clockwise and the other counterclockwise.

3. In a ditch forming machine, the combination which comprises an elongated substantially open hull, a longitudinally positioned shaft journaled in the hull and extended from one end thereof, a tubular shaft positioned on and rotatably mounted on said longitudinally positioned shaft, a rotary cutter having a hub with radially disposed blades thereon carried by and fixedly mounted on the outer end of said longitudinally positioned shaft, a similar cutter carried by and fixedly mounted on the said tubular shaft and spaced from the cutter on the longitudinally positioned shaft the diameter of said rotary cutters being sufficient to cut a ditch the width and depth of which is greater than the width and depth of the hull, and means rotating the cutters through the said shafts with one cutter rotating in a direction opposite to that of the other, the tips of the blades of said cutters shaped to provide propelling means for propelling the hull through the ditch formed by the cutters with the hull floating on water therein.

4. In a ditch forming machine, the combination which comprises an elongated substantially open hull, a longitudinally positioned shaft journaled in the hull and extended from one end thereof, a tubular shaft positioned around and rotatably mounted on said longitudinally positioned shaft, a rotary cutter having a hub with radially disposed blades thereon carried by the outer end of said longitudinally positioned shaft, the blades of said cutter having inclined sections at the tips with the outer edges of said inclined sections sloping inwardly from the leading edges of the blades providing propelling means for drawing the hull through a ditch formed by the cutters with the hull floating on water in the ditch, a similar cutter carried by the said tubular shaft and spaced from the cutter on the longitudinally positioned shaft, a counter-shaft journaled in the hull, transmission gears for rotating the counter-shaft from the longitudinally positioned shaft the diameter of said rotary cutters being sufficient to cut a ditch the width and depth of which is greater than the width and depth of the hull and in a direction opposite to that of the longitudinally positioned shaft, a chain trained over sprockets on the tubular shaft and countershaft for rotating the tubular shaft from the counter shaft, and a motor positioned in the hull for rotating the longitudinally disposed shaft.
